UNITED STATES PATENT OFFICE.

WILLIAM READING GULICK, OF BAY HEAD, NEW JERSEY, ASSIGNOR TO
ALEXANDER R. GULICK, OF NEW YORK, N. Y.

DESIGN FOR A COMPARTMENT-PLATE.

SPECIFICATION forming part of Design No. 22,305, dated March 21, 1893.

Application filed February 15, 1893. Serial No. 462,499. Term of patent 14 years.

To all whom it may concern:

Be it known that I, WILLIAM READING GULICK, residing at Bay Head, Ocean county, New Jersey, have produced a new and original Design for Compartment-Plates, of which the following is a full, clear, and exact specification.

My new and original design relates to compartment plates, and consists in the various features, substantially hereinafter more particularly pointed out and illustrated in the accompanying drawings, in which

Figure 1, is a plan view of the plate. Fig. 2, is an obverse view, and Fig. 3, is a transverse section.

The plate is shown as being substantially circular in outline, and as having a body portion A, and a flanged or flared rim B. Extending from the opposite sides of the rim B, is a ridge C, it being shown as segmental in form, the radius of the segment being greater than the radius of the rim of the plate. Between this ridge C, and the rim B, on the outside of the former are ridges E, F, extending between the two and being in practically right lines, while on either side of these ridges, and also extending between the curved ridge C, and the rim B, are the curved ribs G, H, and there are intervening depressions or compartments between the several ridges and the rim of the plate, as well as a main compartment between the inner edge of the segmental ridge and the rim.

The obverse side of the plate, shown in Fig.

2, represents an appearance substantially the 35 counterpart of the top or plan view, in that there is a depression I, corresponding to the segmental rib B, and depressions J, K, L, M, corresponding to the ridges E, F, G, H, and between the depressions are elevated portions, while between the segmental ridges of the plate is a larger elevated surface. On this elevated surface is a segmental ridge extending to a greater or less extent around the outside thereof concentric with the rim of the 45 plate.

The cross section of the plate is shown in Fig. 3, and the ridges and depressions and elevations are clearly illustrated.

The essential or leading features of my de- 50 sign consist in the design for a compartment plate having the general configuration shown in the plan with the ridges and intervening depressions set forth, as well as the general configuration of the obverse of the plate with 55 the complementary ridges and depressions, substantially as shown and described.

What I claim is—

The design for a compartment plate substantially as illustrated and described. 60

In testimony whereof I have signed my name to this specification in the presence of two subscribing witnesses.

WILLIAM READING GULICK.
